CARTON

George E. Whalley, Chicago, Ill., assignor to
 Robert Gaylord, Incorporated, St. Louis, Mo., a
 corporation of Missouri

Application February 23, 1935, Serial No. 7,663

9 Claims. (Cl. 229—52)

My invention relates to a carton and specifically to a carton formed of fiberboard or similar flexible material and adapted for use in shipping and storing heavy merchandise, particularly bottled beer.

One object of my invention is to form the entire carton, including the cover, of a single sheet of material with the minimum of waste.

Another object of my invention is to provide reinforcing means for the carton, particularly at the parts engaged by the hands when lifting the carton.

In the accompanying drawings, which illustrate a carton made in accordance with my invention, Figure 1 is a vertical cross-section, one of the cover members being shown in raised position; Figure 2 is a top view, partly in elevation and partly in section, taken on the line 2—2 of Figure 1; Figure 3 is an end view; Figure 4 is a bottom view, partly in elevation and partly in section, taken on the line 4—4 of Figure 1; Figure 5 is an enlarged section through one end of the carton taken on the line 5—5 of Figure 3; Figure 6 is an enlarged view of a portion of one end of the carton; Figure 7 is a plan view of the blank from which the carton is formed; Figure 8 is a vertical cross-section showing a slight modification; and Figure 9 is a bottom plan view showing a further modification.

The carton is formed of a single sheet of fiberboard or similar material stamped out in the shape shown in Figure 7 and divided by longitudinal crease lines 1 and 2 into a central and a pair of lateral portions. Cross crease lines 3 divide the central portion into a pair of end panels 4, a pair of side panels 5, and a fastening strip 6. The portion of the blank extending beyond the crease line 1 is divided by slits 7 which are continuations of the creases 3, into a pair of bottom flaps 8, carried by the panels 4, and a pair of bottom flaps 9, carried by the panels 5. The portion of the blank extending beyond the crease line 2 is provided adjacent its edge with a third crease line 10 and is divided by cuts 11 into four parts. The cuts 11 are so positioned that two of the parts, forming reinforcing flaps 12, are of less width than the panels 4 by which they are carried, while the other two parts are of greater width than the panels 5 by which they are carried. The cuts 11 terminate short of the crease line 2 and are connected with the intersection of crease lines 2 and 3 by diagonal cuts 13. In this way I obtain the necessary material for the end cover flanges and at the same time secure reinforcement extending entirely across the upper edge of

the panels 4. Cuts 14 forming extensions of the crease lines 3, extend from the edge of the blank to the crease line 10. These cuts, together with crease lines 3 and 10, divide each of the parts carried by the panels 5 into a cover panel 15, a side cover flange 16, a pair of end cover flanges 17, and a pair of fastening tabs 18. The crease line 10 also provides each of the reinforcing flaps with a reinforcing strip 24. Formed in each of the reinforcing flaps 12 are cuts 19 providing a rectangular reinforcing strip 20 detached along three of the edges but integral with the flap at the other. Formed in each of the panels 4 are cuts 21 providing hand-hold blinds 22. Cuts 19 and 21 are so positioned with respect to crease line 2 that when the reinforcing flap is bent over upon the panels 4, the hand-holds formed by such cuts will register. Arranged between the hand-holds and extending across crease line 2, are slots 23.

In forming the carton from the blank the reinforcing flaps 12 are bent over against the inner faces of panels 4, reinforcing strips 20 bent up between the flaps and the panels, as best shown in Figure 5, and secured by staple 25. Reinforcing strip 24 is also bent up between the flap and the panel and secured by staples 26. Flanges 16 and 17 are bent up at right-angles to panel 15 and secured together by staples 27 passing through flange 16 and tabs 18. The blank is now bent into tubular form and secured by staples 28 passing through the fastening strip 6 and the adjacent end plate 4. Finally, bottom flaps 8 are bent over at right-angles to the end panels, the bottom flaps 9 superimposed upon them, and the flaps 35 secured together by staples 29.

While I prefer to fold the strips 24 up between the flap and the panel, it may be left in the plane of the flap, as shown in Figure 8, as the most essential end reinforcing function is secured by the reinforcing flap and the reinforcing strip 20.

In Figure 9, I have shown an alternative construction in which the bottom flaps 9 are first folded over and the flaps 8 superimposed upon them. With either construction two-ply material is secured throughout the entire area of the bottom.

It will be seen that I secure a strong and rigid carton with the use of a minimum amount of material, the bottom being reinforced by the use of two-ply material and the top by the use of flanges around three sides of each cover panel as well as by the use of the reinforcing flaps and strips. The hand-hold blinds 22 normally seal the hand-holds against entrance of light which

has a deleterious effect upon bottled beer. When the carton is to be lifted, the blinds are forced inwardly, as shown in Figure 5, to permit entrance of the fingers into the hand-holds. Upon 5 withdrawal of the hand the blind will spring back into position to exclude the light.

It will be understood that when my carton is used as a beer case it will be provided with the usual partition walls to separate the bottles but 10 these have not been shown as they form no part of the present invention.

Having fully described my invention, what I claim as new and desire to secure by Letters Patent of the United States is:

15 1. A carton having an end wall comprising an end panel and a reinforcing flap superimposed thereon, said wall being provided with a hand hole, and a reinforcing member for the upper margin of the hand hole, said member being positioned between said parts and formed integral with one of them.

20 2. A carton having an end wall comprising an end panel and a reinforcing flap superimposed thereon, said parts being provided with registering hand holes, and a reinforcing member for the upper margin of the hand holes, said member being integral with one of the parts.

25 3. A carton having an end wall comprising an end panel and a reinforcing flap superimposed thereon, said parts being provided with registering hand holes, the hand hole in one of said parts being formed by partially detaching a piece of material therefrom, and a reinforcing member for the upper margin of the hand holes, said reinforcing member being formed by folding said piece of material between the parts.

30 4. A carton comprising an end panel and a reinforcing flap superimposed thereon, said parts being provided with registering hand holes, a reinforcing member for the upper margin of the hand holes, said member being integral with one of the parts, and a second reinforcing member below the hand holes, said second named member being formed by folding over the lower edge of 45 the flap.

40 5. A carton comprising an end panel and a reinforcing flap superimposed thereon, said parts being provided with registering hand holes, said hand holes being formed by partially detaching pieces of material from the panel and flap, one of said pieces being folded between the parts to form a reinforcing member for the upper margin of the hand holes, and the other piece form-

ing a blind to prevent entrance of light into the carton.

5 6. A carton comprising an end panel and a reinforcing flap superimposed thereon, said parts being provided with registering hand holes, said hand holes being formed by partially detaching pieces of material from the panel and flap, the piece carried by the panel forming a blind to prevent entrance of light, the piece carried by the flap being bent over to form a reinforcing member 10 for the upper margin of the hand holes, and a second reinforcing member below the hand holes formed by folding over the lower edge of the flap.

15 7. A carton formed of a single sheet of material comprising side and end panels, two pair of flaps carried by said panels and secured together to form a reinforced bottom, flaps carried by said end panels, said flaps being superimposed upon and secured to said end panels to form a reinforced end wall, a portion of each flap being folded over between the flap and the adjacent panel to form a secondary reinforcement, slots in the upper edges of the end walls, cover panels carried by the side panels, and flanges on the 20 cover panels adapted to enter said slots.

25 8. A carton formed of a single sheet of material comprising side and end panels, two pair of flaps carried by said panels and secured together to form a reinforced bottom, flaps carried 30 by said end panels, said flaps being superimposed upon and secured to said end panels to form a reinforced end wall, a portion of each flap being folded over between the flap and the adjacent panel to form a secondary reinforcement, slots 35 in the upper edges of the end walls, cover panels carried by the side panels, side flanges on the cover panels, and end flanges on the cover panels and secured to the side flanges, said side flanges being adapted to enter the slots.

40 9. A blank for forming a one-piece carton consisting of an approximately rectangular sheet of material comprising a pair of side panels, a pair of end panels, a bottom flap carried by each of said side and end panels, a reinforcing flap carried by each end panel, said reinforcing flaps at their outer ends being of less width than the end panels, a cover panel carried by each side panel, a side flange carried by each cover panel, and a pair of end flanges carried by each cover panel, 45 three of said end flanges being formed from material removed from the end flaps.

GEORGE E. WHALLEY.
